UNITED STATES PATENT OFFICE.

J. A. NORRIS, OF PHILADELPHIA, PENNSYLVANIA.

JOURNAL-BOX.

Specification of Letters Patent No. 20,363, dated May 25, 1858.

To all whom it may concern:

Be it known that I, JAS. A. NORRIS, of Philadelphia, in the county of Philadelphia, in the State of Pennsylvania, have invented 5 a new and useful Improvement in Boxes for Shafting and other Journals; and I do hereby declare that the following is a full and exact description thereof, reference being had to the accompanying drawings and to 10 the letters of reference marked thereon.

The nature of my invention consists in constructing the box or bearing in which the shaft runs with glands and stuffing boxes, as hereinafter fully described, whereby the passage 15 of any dust or injurious substance to the interior of the box is rendered impossible; also in packing, the sides for the same purpose.

In the accompanying drawings, forming 20 part of this specification, Figure 1, represents a front elevation of my improved box carrying a shaft; Fig. 2, a back elevation of the same; Fig. 3, an end view; Fig. 4, a top view; Fig. 5, a vertical section, on the line 25 x', x' , at Fig. 4; Fig. 6, a vertical section on the line $3, 3$, at Figs. 1, and 4; Figs. 7 and 8, detail views of gland, and Fig. 9, a similar section to Fig. 6, showing the "variable packing," similar letters denoting the same 30 parts in the different views.

A, represents the upper and B, the lower half of the box, which supports, and in which runs, the shaft C. In the "upper portion" A, of said box, is formed an oil chamber h ,—by making an enlargement as seen at c' ,—into which the lubricating material is put through a suitable aperture g , in the top of the enlargement c' , furnished if necessary with a lid or cover. The lower portion B, of said box has formed upon its back side, and extending upward, an arm B', of any desirable shape which is intended to serve the purpose of a "hanger", and the two portions A, and B, are so constructed, as 45 that, when they are clasped around the shaft, C, and secured in their proper relative positions (which is done by means of ordinary bolts, f, f , and suitable flanges or ears on the said portions of said box) there 50 shall be found in each end of the box a cylindrical cavity, around the shaft, C,—or technically, a "stuffing box" to accommodate suitable "packing" material, (as seen at Fig. 5 in the drawing) $i, i, &c.$, and 55 which are furnished with glands D', D, &c., adjusted in and secured in proper relative

position to said stuffing boxes, by suitable bolts E, E, &c., projecting from the upper and lower portions, A, and B, of the box, and furnished with nuts (as shown in the 60 drawings).

The peculiar construction of the glands D, D', &c., will be best comprehended by reference to the different views thereof represented in the drawings, from whence it will 65 be readily observed, that the gland, adapted to the stuffing box in either end of the box, is formed of two parts, marked, D, D', each of which parts is furnished with two ears, d, d' , and holes therein, to accommodate 70 bolts, or screws, e, e , by means of which ears and bolts the two parts, of said gland are united, causing their semi-cylindrical shell to form a perfect cylindrical shell, around the shaft C, and adapted to the stuffing box 75 in the end of the box. At Fig. 7, the portions D, D', are represented as being detached, and withdrawn from around the shaft C, while at Fig. 8, they are shown as being united around said shaft; as also at 80 Figs. 3 and 5, &c.

The upper and lower portions, A, and B, of the box are so constructed, (see Fig. 9,) that when secured around the shaft c , with their "bearing surfaces", in contact with 85 the same, their adjacent surfaces shall not come in contact with each other, but shall remain some distance apart leaving a space occupied, with leather, or other, packing, o , (see Fig. 9,) and in contact with which 90 packing the adjacent sides of the said portions, A, and B, are brought and retained. This packing may be composed of thin layers, of leather or other suitable material, in order that as the box wears away, or that 95 portion of it which forms the bearing surface for the shaft, (which wear is mostly downward, from the weight of the shafting) the upper and lower portions may be brought nearer together; and again in contact with 100 the shaft, by simply removing a layer or so of the said packing, o , and turning down the bolts f, f , &c.

The two parts D, and D', of the glands, are also, so constructed, that, when united around the shaft, c , they shall embrace between them (in like manner to the two portions, A, and B, of the box) a packing, r , (see Fig. 8) which is capable of reduction, in thickness, and the layers of which are withdrawn, when and in the same ratio as, those of the box are extracted. If deemed 105 110 115

expedient, when the bearing surfaces of the box and glands become worn, the packings, *o*, and, *r*, of the former and latter may be entirely removed and the bearing re-bored.

5 The details, of my improved box, it is obvious may be varied without changing its features of novelty and ability, or losing the main features of construction upon which depend its advantages and perfect

10 operation, which latter, I will now explain and which will be readily understood from what has already been said of its construction.

15 The lower portion being placed (in the proper position) beneath, and having its bearing surface in contact with, the shaft, *C*, or supposing the said portion, *B*, already suspended and secured in place by its hanger or arm, *B'*, and the shaft, *C*, placed 20 in said portion, making its relative position with the latter, such as before described, the upper part *A*, is placed over said shaft, *C*, and portion, *B*, as shown in the drawings, having first had placed between it and the 25 said lower portion, the requisite amount of packing, *o*, and is secured to the portion, *B*, by bolts *f*, *f*, *f*, *f*. The parts *D*, *D'*, of the glands are then placed one above and the other below, the shaft (as seen in the drawings) with the requisite packing, *r*, between 30 said parts *D*, and *D'*, and are united and secured by their respective bolts *e*, *e*, *e*, *e*, and ears, *d*, *d*, *d'*, *d'*, when the said glands, are run, on the shaft, *C*, into, their respective 35 stuffing boxes, formed as before described; the said stuffing boxes having been furnished with suitable packing, *i*, *i*, and are

adjusted and secured therein by the bolts *E*, *E*, &c., passing through them, and furnished with nuts, as before described. The 40 parts having been all thus relatively placed and secured together, the clamping pressure, coming upon the packings, *o*, and, *r*, the bearing surfaces of the box come in contact with the shaft, *C*, without creating any 45 more friction than is actually necessary.

The great advantages arising from the construction of boxes, for shafting, as above described, are—firstly, a perfect retention of the oil or other lubricating material, bestowed upon the shaft where it comes in contact with the box; secondly, its preclusion of all dust, or other injurious matter to the bearings.

Having fully described the construction 55 of my improved gland box for shafting and explained its operation, what I claim therein as new and desire to secure by Letters Patent of the United States is:—

1. The combination of the glands *D*, *D'*, &c., with a box *A*, having stuffing boxes formed in each end; substantially as and for the purpose herein described.

2. Arranging a packing, *o*, between the adjacent sides of the box as described 65 whereby the entrance of any dust between said sides is rendered impossible.

In testimony whereof I have hereunto set my hand this eighth day of April 1858.

JAS. A. NORRIS.

Witnesses:

SEPTIMUS NORRIS,
Wm. W. JEFFERSON.
